UNITED STATES PATENT OFFICE.

WILLIAM THOMAS HUNT, OF MANCHESTER, ENGLAND.

STEAM SEPARATOR.

Application filed May 23, 1921. Serial No. 472,024.

(GRANTED UNDER THE PROVISIONS OF THE ACT OF MARCH 3, 1921, 41 STAT L., 1313.)

To all whom it may concern:

Be it known that I, WILLIAM THOMAS HUNT, subject of the King of Great Britain and Ireland, and resident of Manchester, in the county of Lancaster, England, have invented certain Improvements in Steam Separators (for which I have filed applications in England Feb. 20, 1920, and Nov. 22, 1920, Patent No. 168,077), of which the following is a specification.

This invention relates to improvements in steam separators of the internal type for use inside Lancashire, Cornish and like boilers and which with modifications may be made applicable to marine, locomotive and other steam boilers, the object being to obtain the separating effect of a novel arrangement of baffle plates which provide distinct passages for the steam and shelter for the moisture and solid matters in suspension when these latter are once separated from the saturated steam, the arrangement being such that it is impossible for the moisture to again cross the path of the steam and become entrained in it as such steam is leaving the boiler, a further feature providing for the return of the separated moistures to and below the water level in the boiler. A still further object of my invention is to enable deposited dirt and the like to be removed from the separator to the exterior of the boiler whilst not interfering with the operation of the separator within the boiler.

My invention will be fully described with reference to the accompanying drawing in which—

Fig. 1, is a side elevation of an apparatus constructed in accordance with my invention,

Fig. 2, plan of same,

Fig. 3, vertical section on line 3—3 of Fig. 1,

Fig. 4, sectional elevation to an enlarged scale of portions of the baffle plates,

Fig. 5, plan of same, and

Fig. 6, side elevation.

With the aforesaid objects in view my invention consists of a steam separator having an external housing or casing *a* which when used for Lancashire and Cornish boilers is partly rectangular in cross section and partly curved, usually semi-circular as to its lower portion *b* and rectangular, or

partly so, as to its upper portion *c* though the semi-circular portion may be re-placed by a construction of V-shaped trough form. The housing may be of any suitable length, width, and height and its lower portion be provided with one or more outlets *d* entering the water space of the boiler. The aforesaid outlets may be extended in the form of tubes *e* which may themselves only enter the water space, the main structure of the separator lying above the normal level of the water in the boiler. The upper side of the housing is provided with a pipe or conduit *f* directly opening into the junction valve standpipe which controls the passage of the steam from the boiler to the service required, said pipe *f* at its lower end opening into the steam space *m* of the separator. Further, the pipe *f* may be arranged at any suitable position in the length of the housing and if more than one pipe is used in the latter, these would be connected by a chamber or pipe.

Within the main housing at its lower side I arrange a casing *g* of less size so as to leave a space between itself as at *h* and the housing and above the upper edges of this and within the housing I arrange a number of baffle plates *i* together forming a V-shaped or roof construction as shown more particularly in Figure 3, a number of such plates being arranged one above the other. Each baffle plate viewed in side elevation is bent so as to form rectangular corrugations *j* though I do not confine myself to this character of corrugation as they may be of any other suitable shape but I find the rectangular type very efficient. The side walls of the corrugations are provided with slots *k* of suitable length and width so that when a superposed series of plates is arranged within the housing a series of inclined passages *m* at each side of the vertical centre of the separator is formed, a steam space *m* being left below the lowest of the plates and the inside of the inner casing. The bottoms of the corrugations of the corrugated plates rest against each other so that the channels of the corrugations come opposite to each other, each pair of channels or corrugations forming a passage *m*. The outer ends of the passages between the plates open into the space *h* between the outer housing and the inner casing. The

upper edges of the plates rest against longitudinal plates *n* and the whole structure is tied together by bolts *o* and nuts *p* where required the latter bearing against narrow longitudinal plates *q*. End plates *r* are fitted to make the only passage for the steam to enter through the baffles.

When a separator constructed as described is in use steam passes from the outside of the baffle plates *i* into the steam space *m*¹ through the slots *k* in such plates, the arrangement of the latter being such that it has to pass in a sinuous or tortuous course through the slots *k* and passages *m* before passing from the steam space *m*¹ to the outlet to the junction valve stand pipe. In doing this the moisture contained in the steam is deposited upon the surfaces of the plates within the passages *m* from whence it discharges itself downwards to the space *h* between the inner casing and housing of the apparatus from whence it finds its way back to the water space of the boiler. In this way the steam is allowed to escape through to the junction valve in a substantially dry condition. The baffle plates arranged as described also prevents scum, dirt or the like passing along with the steam to the junction valve.

A further feature of my invention comprises means for enabling dirt or the like deposited by the steam to be removed from the separator to the outside of the boiler. Thus a certain amount of dirt or mud may lodge within the space *h* and in order to remove this I connect to the tubes *e* a pipe or chamber *s* of any suitable shape in cross section and of required length both ends of the pipe being closed except that at one end a pipe *s*¹ is led from it to the outside of the boiler. This pipe is provided with a valve of any approved construction. The pipe or chamber *s* is provided at one or both sides

with a number of openings *t* covered with slack valves *u*. Normally these valves are free to open outwardly to allow water from the separator to pass into the water space of the boiler, but become tightly closed when the tap on pipe *s*¹ is opened for the purpose of withdrawing the deposited mud which it does by causing a sudden inrush of steam into and through the whole of the separator baffles, then by way of the space in the housing through the vertical pipes and along the horizontal pipe or chamber to the outside of the boiler, the mud being discharged to a suitable receptacle or drain. In this way a thorough scavenging of the apparatus takes place. The tap is then closed and the separator proceeds to act again in the normal way.

What I claim as my invention and desire to secure by Letters Patent is:—

A steam separator, comprising an outer trough-shaped casing provided with outlets for steam and for water, an inner trough-shaped casing having sides of less height than the sides of the outer casing, a water space being formed between the bottoms of the two casings, and two series of superposed corrugated plates arranged at an angle to each other with their upper and adjacent end portions projecting above the top of the outer casing and their outer and lower ends bearing against the sides of the outer casing, said plates being supported on the top edges of the inner casing and having openings in the sides of their corrugations for the passage of wet steam, said plates being adapted to discharge condensed water from the lower ends of their corrugations into the said water space.

In testimony whereof I have hereunto set my hand.

WILLIAM THOMAS HUNT.
